UNITED STATES PATENT OFFICE.

PETER MADSEN, OF LOS ANGELES, AND LE ROY M. TOMS, OF MAYWOOD, CALIFORNIA,
ASSIGNORS TO MADSEN IRON WORKS, A CORPORATION OF CALIFORNIA.

COMBINATION WAFFLE STOVE AND GAS PLATE.

Application filed July 18, 1923. Serial No. 652,288.

To all whom it may concern:

Be it known that we, PETER MADSEN and LE ROY M. TOMS, citizens of the United States, the former residing at Los Angeles, and the latter residing at Maywood, in the county of Los Angeles, State of California, have invented a new and useful Combination Waffle Stove and Gas Plate, of which the following is a specification.

10 This invention relates to stoves and relates particularly to an improvement in waffle stoves having features which enable the use of the stove as a gas plate, and ease of cleaning the parts thereof.

15 It is an object of the invention to provide a waffle stove having a waffle iron base which may be readily removed so as to permit the cleaning of the stove burner and adjacent parts, this waffle iron base being provided 20 with engagement means for engaging the sub-structure in such a manner that the waffle iron base constitutes a rigidly secured part of the stove which is held in place without the use of screws or bolts and may 25 be readily removed for the purpose of cleaning. The structure of the stove is such that when the waffle iron base is removed, the sub-structure may be employed as a gas 30 plate upon which the ordinary cooking utensils may be placed.

The especial advantages of the invention and further objects thereof will be made evident hereinafter.

Referring to the drawing which is for 35 illustrative purposes only:

Fig. 1 is a vertical cross section through a waffle stove embodying the features of my invention.

Fig. 2 is a section taken on a plane represented by the line 2—2 of Fig. 1.

In the form of my invention shown in the drawing, a sub-structure 11 is provided which supports a waffle iron base 12 in which a waffle iron 13 is operatively held. The sub-structure 11 is formed of longitudinal channels 15 and 16 which are disposed with the legs 17 thereof inwardly directed, and which have supporting legs 18 extending downwardly therefrom. The legs 18 are 40 formed of angle members preferably formed from metal plates stamped or bent to provide perpendicularly extending webs 19. Supported upon the channels is a grid or grate 20 having a central opening 21 therein in the form of a multi-pointed star fig-

ure, the points 22 of which are separated by radially projected arms 23, integrally formed with the grate 20. The tips 25 of the star points 22 are disposed upon a common circle as will be made evident in Fig. 2. 60

The waffle iron base 12 forming part of the stove is comprised of a conical shaped shell 27 having its greatest diameter at the lower edge 28 thereof and tapering inwardly to the upper edge 26 thereof, which edge defines the opening in which the waffle iron 13 is placed, there being formed at the rear of the waffle iron base 12 an arcuated vertical wall 29 having a socket 30 formed at the upper end thereof for receiving the ball 70 hinge 31 of the waffle iron 13, this vertical wall merging with the sloping wall of the shell 27 as indicated at 33. The lower edge 28 of the base 12 is of greater diameter than the distance across the star 21, and when the waffle iron is placed in operative position upon the grate 20, the edge 28 rests outside the points 25 of the star 21, so that all heat passing therethrough from the burner 35 is 75 directed into the interior of the shell, and is therefore applied to the waffle iron 13, consequently preventing the wasting of heat upwardly around the outside of the waffle iron base. 80

For the purpose of removably securing the waffle iron base 12 upon the grate 20, engagement members 36 and 37 are provided. The engagement member 36 provides an inwardly projecting portion 38 from which there downwardly extends a leg 39. By forming the downwardly extending leg 39 at the inner end of the projecting portion 38, it is possible to bring this leg in a position within the diameter of the lower edge 28 of the base 12 so that it will 85 project downwardly into the forward point 22 of the star opening. The rearward engagement member provides an inwardly extending leg 40, which projects inwardly from the shell 27, a downwardly extending web portion 41, and an outwardly extending leg 42, thus providing a U shaped hook, having the upper leg thereof integrally formed with the shell 27. The web 41, being disposed at the inner end of the leg 40, will project downwardly in the rearward star point 22, thus enabling the lower leg 42 to extend rearwardly under the grate 20. The base 12 when placed as shown in the drawing, forms a part of the waffle stove. 100 105 110

and is securely held in place against movement due to side pressure upon the handles 49 of the waffle iron, which side pressure is generally exerted when the waffle iron is 5 being turned over and has a tendency to displace the waffle iron base 12. The only way in which the base can be removed is by first lifting the forward end of the base so that the leg 39 will be raised out of engagement with the grate opening, and then pulling the base 12 forwardly to disengage the hook shaped member 37, whereupon the base may be lifted from the grate. Thus it will be evident that one of the functions of the 15 hook projection 37 is to prevent vertical displacement of the rear portion of the base 27, it being pointed out that if said projection were similar to the projection 36 instead of having a hook engagement beneath the grid 20, an excessive downward and forward pressure upon the waffle iron handles 49 would cause the base to be tilted, the forward lower edge of the base acting as the fulcrum and the rear position of the 20 base swinging upwardly. This would also be liable to take place if the waffle iron were, by accident, dropped while being manipulated, thus causing the base to jump out of its proper engagement with the grid. When 25 the base is thus removed, the stove may be easily cleaned, as will be readily recognized, and the sub-structure 11 then has the form of a gas plate and may be used as such owing to the rigid construction of the radially 30 extending arms 23 and the supporting structure which are capable of supporting the weight of heavy utensils which might be placed thereupon.

In the drawing, a single unit of a waffle 40 stove is shown; but it will be readily recognized that a battery of these stoves may be integrally constructed by placing the grates 20 in consecutive arrangement as indicated at 50, the angle members 15 and 16 being 45 likewise extended to support the consecutive grate members. The burner 35 in accordance with the standard construction is provided with an air mixer 52 at the forward end thereof and is fed with gas from a gas 50 supply pipe 53 through a valve 54. The rearward end of each burner 35 is provided with a hook 55 which rests upon a small longitudinal angle 56 extended between the rearward legs 18.

We claim as our invention:

55

1. In a device of the character described, the combination of: a supporting structure; a grate supported on said structure, said grate having an opening therein for the passage of heat and flame; waffle irons; a waffle iron base of greater diameter than said opening; a hooked engagement member at one side of said base, said member comprising a leg extending inwardly from the lower edges of said base to a point within 60 said opening, a web extending downwardly through said opening, and a leg extending outwardly from the lower end of said web, underneath the edge confining said opening; and an engagement member at the opposite 65 side of said base, said engagement member comprising a leg extending inwardly from the edge of said base and a leg extending downwardly from the inner end of said inwardly extending leg, through said grate 70 opening.

2. In a device of the character described, the combination of: a supporting structure; a grate supported on said structure, said grate having an opening therein for the passage of heat and flame; waffle irons; a waffle iron base of greater diameter than said opening; a hooked engagement member at the rear of said base, said member comprising a leg of said base to a point within 80 said opening, a web extending downwardly through said opening, and a leg extending outwardly from the lower end of said web, underneath the edge confining said opening; and an engagement member at the 85 front of said base, said engagement member comprising a leg extending inwardly from the edge of said base and a leg extending downwardly from the inner end of said inwardly extending leg, through said grate 90 opening.

3. A cooking utensil base of the character described, comprising: an annular ring arranged to receive a utensil; a hook extending downwardly and outwardly at one side 100 of said ring; and a downwardly projecting engagement lug substantially opposite to said hook.

In testimony whereof, we have hereunto set our hands at Los Angeles, California, 105 this 13th day of July, 1923.

PETER MADSEN
LE ROY M. TOMS.
